UNITED STATES PATENT OFFICE

NATHAN EDWARD SARGEANT, OF MONTESANO, WASHINGTON

TRIMMING MACHINE

Application filed April 24, 1928. Serial No. 272,583.

This invention relates to a trimming machine and primarily it is an object of the invention to provide a device of this kind for trimming lumber in saw mills, although it is to be understood that it is possible to use the machine with equal advantage for other purposes.

Another object of the invention is to provide a device of this kind comprising a movable carriage together with means whereby the travel of such carriage is readily controlled and whereby the saw mounted upon such carriage may be driven irrespective of the changing positions of the carriage.

The invention consists in the details of construction and in the combination and arrangement of the several parts of my improved trimming machine whereby certain important advantages are attained and the device rendered simpler, less expensive and otherwise more convenient and advantageous for use, as will be hereinafter more fully set forth.

The novel features of my invention will hereinafter be definitely claimed.

In order that my invention may be the better understood, I will now proceed to describe the same with reference to the accompanying drawings, wherein:

Figure 1 is a view in side elevation of a trimming machine constructed in accordance with an embodiment of my invention, certain of the parts being broken away, the carriage being in motion in the direction indicated by the arrow;

Figure 2 is a view in front elevation of the structure as illustrated in Figure 1;

Figure 3 is a vertical sectional view taken through the structure as illustrated in Figure 1 with certain of the parts in elevation and a guard or shield indicated by broken lines, the carriage being in motion in the direction indicated by the arrow;

Figure 4 is a sectional view taken substantially on the line 4-4 of Figure 3, the guard or shield being also diagrammatically indicated by broken lines;

Figure 5 is an enlarged detailed sectional view taken substantially on the line 5-5 of Figure 3;

Figure 6 is a detailed sectional view taken substantially on the line 6-6 of Figure 4.

As disclosed in the accompanying drawings, H denotes an elongated housing of desired dimensions and which, when the device is being used in a saw mill for lumber trimming, is preferably supported with its longitudinal axis vertically disposed. Snugly engaged within the housing H for sliding movement is a boxing or carriage B. One end portion of the boxing or carriage B is provided with opposed bearing blocks 1 which are slidably received between the guide blocks 2 arranged at said end portion of the boxing or carriage B. The bearing blocks 1 after being applied are effectively held against displacement by the plate 3 which partially closes an open side face of the boxing or carriage B.

The guide blocks 2 and the bearing blocks 1 coacting therewith are provided to facilitate the proper application of the shaft or saw arbor 4 which is rotatably supported by the bearing blocks 1 and extends outwardly through the outstanding bosses 5 carried by the bearing blocks 1. These bosses 5 ride within the slots 6 provided in opposed faces of the housing H.

The shaft 4 substantially midway of the bearing blocks 1 has mounted thereon a sprocket wheel 7, a side face of which abuts an annular collar 8 carried by the shaft 4 and the sprocket wheel is clamped to the collar 8 for rotation with the shaft 4 by the sliding collar 9 having direct clamping contact with the face of the sprocket wheel 7 remote from the collar 8. The collar 9 is adjusted into requisite clamping engagement with the sprocket 7 through the medium of the elongated shank or bar 10 threaded axially of the shaft 4 through an end thereof, said shank or bar 10 having its inner end provided with a cross head 11 having direct engagement with the collar 9. The cross head 11 is adapted to have movement within the slots 12 disposed lengthwise of the shaft 4. The shank or bar 10 is of a length to normally project beyond the end of the shaft 4 in which it is engaged, said extended portion of the shank or bar 10 being provided with a head 14.

Figure 6 is a detailed sectional view taken substantially on the line 6-6 of Figure 4. The housing H is elongated and has a side face H' which is closed by the boxing or carriage B. The side face H' has a slot 15 provided therein. The side face of the carriage B has a slot 16 provided therein. The slot 15 is of a length to receive the shank or bar 10 of the sprocket 7. The slot 16 is of a length to receive the shank or bar 10 of the sprocket 7. The shank or bar 10 is of a length to normally project beyond the end of the shaft 4 in which it is engaged, said extended portion of the shank or bar 10 being provided with a head 14.

angular in cross section so that a suitable implement may be effectively engaged therewith to rotate the shank or bar 10 in the direction desired to either render the collar 9 operative or inoperative with respect to the sprocket 7.

Operatively engaged with the sprocket 7 is an endless chain 15 which is also operatively engaged with a second sprocket wheel 16 at the upper end portion of the boxing or carriage B. This wheel 16 is fixed to a shaft 17 having its extremities rotatably supported by the boxings 18, each of which is slidably mounted within the guideways 19 carried by opposed walls of the boxing or carriage B.

Each of the boxings 18 has in threaded engagement therewith from above a headed shank or member 20 which is freely disposed through the upper or top closed end 21 of the boxing or carriage B and provides means whereby the boxing 18 may be adjusted as required to maintain the chain 15 sufficiently taut. One stretch of the chain 15 is provided with an outwardly directed loop portion 22 which is operatively engaged from within with the guide sprockets 23 and which has its outer portion operatively engaged with a drive sprocket 24. The sprocket 24 is fixed to a shaft 25 rotatably supported by the bearings 26 suitably affixed to a side face 27 of the housing H and at opposite sides of an elongated slot 28 provided in said side wall 27 preferably midway the ends of the housing H, said slot being disposed lengthwise of said wall. The loop 22 is directed through said slot 28 and the sprockets 23 are arranged inwardly of but adjacent to the opposite ends of the slot, said sprockets being carried by the shafts 29 also supported by the bearings 26. Operatively engaged with the bearings 26 and substantially enclosing the bearings 26 and the sprockets 23 and 24 is a cap or casting 30.

The shaft 25 projects a material distance outwardly beyond one of the bearings 26 and has its outer portion supported by an outboard bearing 31 carried by the adjacent side wall of the housing H and outwardly of the bearing 31 is a pulley 32 whereby the shaft 25 through the instrumentality of a belt may be operatively engaged with a suitable source of power. While I particularly refer to a pulley 32 with which a belt is adapted to be engaged, it is to be understood that requisite power may be transmitted to the shaft 25 in any manner which may be preferred.

Upon driving the shaft 25 the chain 15 will be caused to travel to effect the desired rotation of the shaft 4 irrespective of the position of the boxing or carriage B with respect to the housing H upon endwise movement of the boxing or carriage B within the housing H. In other words, the driving connection between the shaft 25 and shaft 4 is such that the shaft 4 will be caused to con-

tinuously operate upon endwise movement or reciprocatory movement of the boxing or carriage B within the housing H.

A sprocket wheel 33 is operatively engaged with a stretch of a sprocket chain 34, said chain being also operatively engaged with a sprocket 35 rotatably supported by the outboard bearing 31 and with a larger sprocket wheel 36 fixed to a shaft 37 rotatably supported by the end portion of the housing H remote from the shaft 4 and extending across a face thereof. The chain 34 passes around the sprockets 35 and 36 and has a stretch thereof operatively engaged with the sprocket 33, said sprocket 33 constituting the driving element for the chain 34 resulting in the requisite rotation of the shaft 37.

The rotation of the shaft 37 is at a speed determined by the ratio of the sprockets 33, 35 and 36.

The shaft 37 substantially central thereof and between the supporting bearings 38 for the shaft has fixed thereto a gear 39 which is constantly in mesh with a rack 40 provided on and extending lengthwise of a rod 41 rigidly secured, as at 42, to the closed end 21 of the boxing or carriage B.

The sprocket 33 is fixed to a shaft 43 mounted between the side members of a substantially U-shaped bearing 44 having its intermediate portion operatively engaged with the housing H whereby the bearing 44 is capable of rocking movement on pivot 44a in a direction toward or from the shaft 25. The shaft 43 also has fixed thereto a wheel 45 the periphery of which is adapted to have frictional contact with the periphery of a pulley 46 mounted upon the shaft 25 so that when the wheel 45 and pulley 46 are in contact, the chain 34 will be caused to travel to rotate the shaft 37 in a manner to move the boxing or carriage B in the direction indicated by the arrow a in Figures 1 and 3. The wheel 45 and the pulley 46 are normally maintained in contact through the instrumentality of a retractile spring 47 of desired tension having one end portion operatively engaged with an extension arm 48 and with the adjacent side wall of the housing H. This arm 48 constitutes, as herein disclosed, an extension of one of the side members of the bearing 44 and is disposed in a direction away from the shaft 43.

As the boxing or carriage B is moved to cause the shaft 4 to travel inwardly of the housing H, said boxing or carriage will come into contact with an inwardly disposed lug 49 carried by an elongated member 50 supported for sliding movement upon an outer face of a wall of the housing H by the bearings 51. The lug 49 extends within the housing H through a suitably positioned slot 52 of requisite length. The inner end portion of the member 50 is operatively engaged by a rod 53 or kindred member with the end portion

of an arm 54 normally disposed in a direction substantially at right angles to the path of travel of the member 50. This arm 54 is carried by a head 55 supported by the housing 5 H, as at 56, for rocking movement toward or from the arm 48. This head 55 at its end remote from the arm 54 is provided with an outstanding lug 57 disposed in a direction toward the arm 48 and which, when the arm 54 is in its normal position, has its free end portion slightly spaced therefrom.

When the member 50 is moved by contact of the traveling boxing or carriage B with the lug 49, the head 55 will be rocked in a direction to bring the lug 57 into contact with the adjacent marginal portion of the arm 48 and thereby swing the shaft 43 in a direction to disengage the wheel 45 from the pulley 46 whereby the further travel of the boxing or carriage B is stopped. Such movement of the member 50 under the action of the boxing or carriage B is sufficient to cause the lug 57 to engage within a notch 58 provided in the co-acting marginal portion of the arm 48 whereby said arm 48 is locked against the action of the spring 47 until the lug 57 is released from the arm 48.

As the wheel 45 is moved away from the pulley 46 the periphery of said wheel 45 is brought into braking engagement with a brake shoe 59 carried by an end portion of a lever 60. This lever 60 is supported substantially midway its ends, as at 61, by the housing H for swinging movement in a direction to permit the brake shoe 59 to move toward or from the wheel 45. The end portion of the lever 60 remote from the shoe 59 has engaged therewith a retractile spring 62 also suitably connected with the adjacent wall of the housing H, said spring 62 having requisite tension to cause the shoe 59 to have such contact with the wheel 45 when moved into release position with respect to the pulley 46 to effectively brake said wheel 45 together with the shaft 43 against rotation.

The head 55, or more particularly the lug 57 thereof, is normally maintained in an inoperative position with respect to the lever 48 through the medium of the retractile spring 63 interposed between and secured to the lever 48 and the arm 54. The tension of the spring 63 is also sufficient to normally maintain the member 50 in its retracted position, or with the lug 49 thereof at the inner end of the slot 52 through which said lug extends.

When it is desired to permit the boxing or carriage B together with the parts associated therewith to have movement in the opposite direction, as by gravity, the shoe 59 is moved out of engagement with the wheel 45 by requisite pull upon the end portion of the lever 60 remote from the shoe 59.

As herein disclosed, this end portion of the lever 60 is provided with an extension arm 64 disposed substantially at right angles to

the lever 60 and extending in a direction toward the shaft 4 and the free end portion of this arm 64 is operatively engaged through the medium of a rigid link 65 with a pivoted operating lever 66. The arm 64 has its opposite end portions offset one with respect to the other and thereby providing an intermediate cross member 67 which, upon further pull being imposed on the arm 64, will bring such member 67 into contact with the arm 48 and swing the same a distance to effect the release of the lug 57 from the arm 48. In the operation of this device, the retractile spring 62 normally holds the lever 60 in substantially horizontal position and the retractile spring 47 normally holds the outer end of the lever 48 in a substantial horizontal position so that the wheel 45 will normally engage the operating or power wheel 46 thereby rotating the pinion 33 which, in turn, moves the chain 34 and cooperatively turns the gear member 39 so as to pull the carriage B upwardly. When the carriage B has moved upwardly to the point where it will engage the lug 49, the elongated member 50 will be moved upwardly. With the movement of the member 50 upwardly, the connecting link 53 will pull the arm 54 upwardly thereby causing the outstanding lug 57 to engage the arm 48 in the notch 58. When the lug 57 engages the arm 48, the arm 48 will be rocked on the pivot 44a and will carry the wheel 45 out of engagement with the power wheel 46 a sufficient distance to cause the wheel 45 to contact with the braking member 59 on the arm 60. In this position, the carriage B may be held in upstanding position or at the end of the vertical travel thereof.

When it is desired to permit the carriage to move downwardly, the pivoted operating member 66 may be pulled downwardly by the workman and the downward movement of the lever 66 will disengage the braking member 59 from the wheel 45. At the same time, the outstanding cross member 67 will engage the upper edge portion of the arm 48 and pull the same downwardly thereby permitting the wheel 45 to idle, and when the wheel 45 is permitted to idle, the carriage B will be able to move downwardly by gravity. It is of course understood that the weight of the carriage B is sufficient so that it will be able to move downwardly in the housing H without the necessity of any mechanical means to effect the downward movement.

It will be obvious from the foregoing that the downward movement of the carriage may be cushioned or retarded by slight release or upward movement of the lever 66 which will permit the spring 62 to retract and rock the arm 60 so as to permit the braking member 59 to contact with the wheel 45 during the idle movement thereof. Upon release of the lug 57 from the arm 48, the spring 47 will operate to return the wheel 45 into contact

with the pulley 46 and the spring 62 will operate to return the lever 60 to its normal position. It is to be understood that when the lever 60 is in its normal position the spring 62 is substantially inactive.

5 The shaft 4 projects beyond a side of the housing H and said extended portion constitutes a mandrel upon which is mounted in any preferred manner a circular saw S of a type 10 preferred for the working operation to be performed, such as trimming.

The outer or extended end portion of the rod 41 carries a bumper spring 68 for contact with the adjacent head or end 69 of the housing H as the boxing or carriage B moves 15 in a direction away from said head 69.

19 As I have hereinbefore particularly stated, my improved device is a lumber trimmer but it is to be understood that it can be employed with equal facility as a rip saw.

It is also to be understood that the walls 23 of the housing H and the boxing or carriage B are preferably made of metal although I do not wish to be understood as limiting myself in this respect. It is to be understood, however, that the carriage B and the parts 28 associated therewith are of sufficient weight to require but slight effort on the part of the workman in order to assure the saw S having proper engagement with the work during the 33 sawing operation.

37 From the foregoing description it is thought to be obvious that a trimming machine constructed in accordance with my invention is particularly well adapted for use by reason of the convenience and facility with which it may be assembled and operated, and it will also be obvious that my invention is susceptible of some change and modification without departing from the principles and spirit thereof and for this reason I do not wish to be understood as limiting myself to the precise arrangement and formation of the several parts herein shown in carrying out my invention in practice except as hereinafter claimed.

42 I claim:—

1. A wood working apparatus comprising a vertically disposed housing, a movable carriage mounted in the housing, operating means for moving the carriage upwardly in the housing, carriage stopping means carried by the housing and actuated upon movement of said carriage at a predetermined point in the line of its travel in the housing, and carriage releasing means mounted on the housing and engaging said stopping means and adapted to permit the carriage to gravitate downwardly therein.

46 2. A wood working apparatus comprising a vertically disposed housing, a reciprocable carriage mounted in the housing, operating means for moving said carriage upwardly in the housing, stopping means carried by the housing and adapted to engage said operating

means whereby to stop the upward movement of said carriage at a predetermined point and to hold the carriage against movement, and carriage releasing means mounted on the housing, said releasing means being adapted to hold said stopping means out of engagement with said operating means to permit the carriage to gravitate downwardly therein.

3. A wood working apparatus comprising a vertically disposed housing, a carriage, a saw arbor rotatably supported by the carriage, power means for said saw arbor, a gear rack secured to said carriage at the upper end thereof, rack engaging means mounted on the housing, driving means, operating means for said rack engaging means whereby to move the carriage upwardly in the housing, releasing means mounted on the housing and adapted to disengage said gear rack operating means from said driving means, said releasing means being actuated by said carriage at a predetermined point in the line of travel thereof, brake means for holding the carriage in upward position, and manually operated means engaging said brake means to disengage said brake from said gear rack operating means while maintaining said gear rack operating means disengaged from said driving means whereby to permit said carriage to gravitate downwardly in the housing.

4. A wood working apparatus comprising a vertically disposed housing, a carriage adapted for reciprocal movement in the housing, a saw arbor, means for rotatably mounting said saw arbor on the carriage, operating means for said saw arbor, a gear rack mounted on said carriage and adapted for movement therewith, rotatable rack engaging means mounted on the housing, releasable operating means for said rack engaging means, driving means for said releasable operating means, rockable releasable means mounted on the housing and adapted to engage said releasable operating means, means for rocking said releasable means when said carriage has reached a predetermined point in the line of travel thereof, brake means rockably engaging said releasable operating means for holding said carriage in upward position, and manually operated means engaging said brake means and said operating means whereby to disengage said brake from said releasable operating means while maintaining said operating means disengaged from said driving means to permit the carriage to gravitate downwardly in the housing.

5. A wood working apparatus comprising a vertically disposed housing, a reciprocable carriage mounted in the housing, a saw arbor rotatably mounted on the carriage, operating means for said saw arbor, a gear rack mounted on the carriage, a rotatable gear

- mounted on the housing and adapted for engagement with said gear rack, releasable operating means mounted on the housing and adapted for engagement with said gear, an 5 elongated bar slidably mounted on the housing adjacent the upper end portion thereof, an inwardly extending arm mounted on said bar and adapted for movement therewith, said arm being adapted for engagement with 10 said carriage upon upward movement of the carriage, mechanical releasing means for said gear operating means, connecting means connecting said elongated bar and said releasing means, brake means for holding said 15 carriage in upward position, and manually operated releasing means releasing said brake means whereby to permit the carriage to gravitate downwardly in the casing.
6. A wood working machine comprising 20 a vertically disposed housing, a carriage slidably mounted in said housing and adapted for vertical movement therein, a saw arbor rotatably mounted on said carriage, operating means for said saw arbor, a gear rack 25 mounted on said carriage, a rotatable gear mounted on the housing and adapted to engage said gear rack, a shaft for said gear, a rotatable member on said shaft, an operating member, a second rotatable member 30 swingingly mounted on the housing and engaging said operating member, a flexible member engaging said first and said second rotatable members, means for swinging said second rotatable member into inoperative position when said carriage has reached a predetermined point in the line of travel, braking 35 means mounted on the housing and engaging said second rotatable member whereby to hold said rotatable members and said carriage against movement, and manually operable means for releasing said brake whereby to permit said second rotatable member to idle, said carriage gravitating downwardly when said second rotatable 40 member is held in idling position.
7. A wood working machine comprising a vertically disposed housing, a carriage slidably mounted in the housing and adapted for vertical movement therein, a saw arbor rotatably mounted on the carriage, operating means for said saw arbor, a power member, operating means for moving said carriage and engaging said power member, mechanical stop means mounted on the housing and adapted for engagement with the carriage when the carriage has reached a predetermined point in the housing whereby to release said operating means from said power 50 member and coercively hold said carriage upwardly, means adapted to engage said mechanical stop means whereby to release the carriage from said mechanical stop means, said carriage gravitating downwardly upon release from said stop means, and cushioning means for cushioning the downward movement of the carriage.
8. A wood working machine, a supporting structure, a carriage coacting with said structure for sliding movement in opposite directions, mechanical means for imparting upward movement to the carriage, said mechanical means including a rotatable element operatively engaged with the carriage, an endless member operatively engaged with the 55 rotatable member, a drive shaft, a pulley carried by the shaft, a bearing movable toward or away from the drive shaft, a shaft carried by said bearing, a pulley carried by the second shaft, means for constantly urging the bearing in a direction toward the drive shaft to normally maintain the pulley of the shaft carried by the bearing in operative engagement with the pulley of the drive shaft, a rocking member carried by the structure 60 and coacting with the movable bearing upon rocking movement in one direction to carry the pulley on the movable bearing away from the drive shaft to release the shaft of said bearing from the drive shaft, a brake 65 coacting with the rocking member whereby to hold the carriage upwardly, and manually operated means for disengaging said brake from said driven pulley and for releasing said rockable member from engagement with said movable bearing while simultaneously maintaining said movable bearing and driven pulley disengaged from said drive pulley whereby to permit the carriage to gravitate downwardly.
9. A wood working machine, a supporting structure, a carriage coacting with said structure for sliding movement in opposite directions, mechanical means for imparting upward movement to the carriage, said mechanical means including a rotatable element operatively engaged with the carriage, an endless member operatively engaged with the 70 rotatable member, a drive member, a swingable control member adapted for movement toward or from the drive member, means for constantly urging the control member in a direction toward the drive member to normally maintain the control member in operative engagement with the drive member, a rocking member carried by the structure and engaging the control member to carry the control member away from the drive member to release the control member from the drive member, and locking 75 means operating upon predetermined travel of the carriage by the mechanical means for swinging the control member in disengaged position with respect to said drive member whereby to stop the upward movement of the carriage, and manually operated means for holding said control member out of engagement with said locking means and said drive member whereby to permit the carriage to gravitate downwardly.
10. A wood working machine, a supporting structure, a carriage coacting with said structure for sliding movement in opposite directions, mechanical means for imparting upward movement to the carriage, said mechanical means including a rotatable element operatively engaged with the carriage, an endless member operatively engaged with the 80 rotatable member, a drive member, a swingable control member adapted for movement toward or from the drive member, means for constantly urging the control member in a direction toward the drive member to normally maintain the control member in operative engagement with the drive member, a rocking member carried by the structure and engaging the control member to carry the control member away from the drive member to release the control member from the drive member, and locking 85 means operating upon predetermined travel of the carriage by the mechanical means for swinging the control member in disengaged position with respect to said drive member whereby to stop the upward movement of the carriage, and manually operated means for holding said control member out of engagement with said locking means and said drive member whereby to permit the carriage to gravitate downwardly.
11. A wood working machine, a supporting structure, a carriage coacting with said structure for sliding movement in opposite directions, mechanical means for imparting upward movement to the carriage, said mechanical means including a rotatable element operatively engaged with the carriage, an endless member operatively engaged with the 90 rotatable member, a drive member, a swingable control member adapted for movement toward or from the drive member, means for constantly urging the control member in a direction toward the drive member to normally maintain the control member in operative engagement with the drive member, a rocking member carried by the structure and engaging the control member to carry the control member away from the drive member to release the control member from the drive member, and locking 95 means operating upon predetermined travel of the carriage by the mechanical means for swinging the control member in disengaged position with respect to said drive member whereby to stop the upward movement of the carriage, and manually operated means for holding said control member out of engagement with said locking means and said drive member whereby to permit the carriage to gravitate downwardly.
12. A wood working machine, a supporting structure, a carriage coacting with said structure for sliding movement in opposite directions, mechanical means for imparting upward movement to the carriage, said mechanical means including a rotatable element operatively engaged with the carriage, an endless member operatively engaged with the 100 rotatable member, a drive member, a swingable control member adapted for movement toward or from the drive member, means for constantly urging the control member in a direction toward the drive member to normally maintain the control member in operative engagement with the drive member, a rocking member carried by the structure and engaging the control member to carry the control member away from the drive member to release the control member from the drive member, and locking 105 means operating upon predetermined travel of the carriage by the mechanical means for swinging the control member in disengaged position with respect to said drive member whereby to stop the upward movement of the carriage, and manually operated means for holding said control member out of engagement with said locking means and said drive member whereby to permit the carriage to gravitate downwardly.
13. A wood working machine, a supporting structure, a carriage coacting with said structure for sliding movement in opposite directions, mechanical means for imparting upward movement to the carriage, said mechanical means including a rotatable element operatively engaged with the carriage, an endless member operatively engaged with the 110 rotatable member, a drive member, a swingable control member adapted for movement toward or from the drive member, means for constantly urging the control member in a direction toward the drive member to normally maintain the control member in operative engagement with the drive member, a rocking member carried by the structure and engaging the control member to carry the control member away from the drive member to release the control member from the drive member, and locking 115 means operating upon predetermined travel of the carriage by the mechanical means for swinging the control member in disengaged position with respect to said drive member whereby to stop the upward movement of the carriage, and manually operated means for holding said control member out of engagement with said locking means and said drive member whereby to permit the carriage to gravitate downwardly.
14. A wood working machine, a supporting structure, a carriage coacting with said structure for sliding movement in opposite directions, mechanical means for imparting upward movement to the carriage, said mechanical means including a rotatable element operatively engaged with the carriage, an endless member operatively engaged with the 120 rotatable member, a drive member, a swingable control member adapted for movement toward or from the drive member, means for constantly urging the control member in a direction toward the drive member to normally maintain the control member in operative engagement with the drive member, a rocking member carried by the structure and engaging the control member to carry the control member away from the drive member to release the control member from the drive member, and locking 125 means operating upon predetermined travel of the carriage by the mechanical means for swinging the control member in disengaged position with respect to said drive member whereby to stop the upward movement of the carriage, and manually operated means for holding said control member out of engagement with said locking means and said drive member whereby to permit the carriage to gravitate downwardly.
15. A wood working machine, a supporting structure, a carriage coacting with said structure for sliding movement in opposite directions, mechanical means for imparting upward movement to the carriage, said mechanical means including a rotatable element operatively engaged with the carriage, an endless member operatively engaged with the 130 rotatable member, a drive member, a swingable control member adapted for movement toward or from the drive member, means for constantly urging the control member in a direction toward the drive member to normally maintain the control member in operative engagement with the drive member, a rocking member carried by the structure and engaging the control member to carry the control member away from the drive member to release the control member from the drive member, and locking means operating upon predetermined travel of the carriage by the mechanical means for swinging the control member in disengaged position with respect to said drive member whereby to stop the upward movement of the carriage, and manually operated means for holding said control member out of engagement with said locking means and said drive member whereby to permit the carriage to gravitate downwardly.

10. A wood working machine, a supporting structure, a carriage coacting with said structure for sliding movement in opposite directions, mechanical means for imparting upward movement to the carriage, said mechanical means including a rotatable element operatively engaged with the carriage, an endless member operatively engaged with the rotatable member, a drive member, a bearing movable toward or from the drive member, a control member rotatable carried by said bearing, means for constantly urging the bearing in a direction toward the drive member to normally maintain the control member in operative engagement with the drive member, a rocking member carried by the structure and the control member upon rocking movement in one direction to carry the control member away from the drive member to release the control member from the drive member, locking means operating upon predetermined travel of the carriage by the mechanical means for swinging the control member into disengaged position from said drive member and hold said control member against rotation and coactively hold the carriage in uppermost position, and release means engaging said locking means whereby to permit idling of said carriage to gravitate downwardly.

In testimony whereof I hereunto affix my signature.

NATHAN EDWARD SARGEANT.
